United States Patent Office.

WILLIAM PARKIN, OF TAUNTON, MASSACHUSETTS, ASSIGNOR TO REED & BARTON, OF SAME PLACE.

Design No. 4,710, dated March 14, 1871.

DESIGN FOR A SPOON OR FORK-HANDLE.

The Schedule referred to in these Letters Patent and making part of the same.

To all persons to whom these presents may come:

Be it known that I, WILLIAM PARKIN, of Taunton, of the county of Bristol and State of Massachusetts, have invented or produced a new and useful Design for a Handle for a Spoon, Fork, or other article of manufacture to which such may be applicable; and I do hereby declare the same to be fully described in the following specification and represented in the accompanying drawing, of which—

Figure 1 denotes a front, and

Figure 2 a rear view of a spoon with a handle formed in accordance with the design.

The handle, at its apex, has the form of a pointed arch, with offsets at its base, and gradually tapers

from the offsets, and is paneled on its opposite sides by a thread extended around the edge.

Within the upper part of the panel, on one side, is a *fleur de lis*, and at or near the middle part of the handle is an ornament in relief, composed of two volutes springing from a single stem and surmounted by a trefoiled rosette, all being as represented.

I claim as my invention—

The design, substantially as shown and described.
WILLIAM PARKIN.
